John A. Whittaker

By S. C. Thomas

Attorney

UNITED STATES PATENT OFFICE.

JOHN A. WHITTAKER, OF DETROIT, MICHIGAN.

LATCH.

Application filed August 13, 1921. Serial No. 491,894.

To all whom it may concern:

Be it known that I, JOHN A. WHITTAKER, citizen of the United States, residing at Detroit, county of Wayne, State of Michigan, have invented a certain new and useful Improvement in Latches, and declare the following to be a full, clear, and exact description of the same, such as will enable others skilled in the art to which it pertains to make and use the same, reference being had to the accompanying drawings, which form a part of this specification.

My invention relates to door latches shown in the accompanying drawings and more particularly pointed out in the following specification and claims.

One object of the present invention is to provide a spring actuated latch adapted to overcome or correct any tendency of the door to sag.

Another object of the invention is to provide a construction adapted to force the door tightly against the casing and to insure the door against rattling.

Another object is to provide a latch of few parts simple in construction and operation and inexpensive to manufacture.

With the foregoing and other objects in view which will appear as the description proceeds the invention further resides in the combination and arrangement of parts and in the details of construction hereinafter described and claimed, it being understood that changes may be made in the precise embodiment of the invention herein disclosed without departing from the spirit of the same.

In the drawings forming part of this specification:

Figure 1 is a cross sectional view through the latch and strike plate, attached respectively to an automobile door, and body of the vehicle;—showing a portion of the rack bar broken away to disclose the operating gear carried by the lock spindle.

Figure 2 is a vertical longitudinal sectional view taken on or about line 2—2 of Figure 1 looking in the direction of the arrows.

Figure 3 is a similar vertical longitudinal sectional view taken on or about line 3—3 of Figure 1.

Figure 4 is an end elevation of the strike plate attached to a fragment of the body.

Figure 5 is an end elevation of the latch showing the latch plate attached to a fragment of a door.

Referring now to the letters of reference placed upon the drawings:

A, indicates an automobile door and B the body or frame of the vehicle. C, denotes the body of the latch and C' the latch plate secured to the door by screws D projecting through the latch plate into the edge of the door. E, indicates the latch bolt provided with a rearwardly projecting shank E' extending through a bracket F rigidly secured to the wall of the latch body. G, denotes a spring sleeved upon the shank between the shoulder E² formed by the relatively larger latch bolt and the bracket F secured to the latch body. H, H, are handles secured to a spindle or shank I, extending transversely through the door and body of the lock. J, denotes a gear mounted upon the spindle I, meshing with a rack bar K, provided at its forward end with lateral extensions K' K' adapted to overlap a pair of spaced lugs E^a projecting from one side of the latch bolt E. The forward or outer end of the latch bolt is beveled in three directions—see E^b, E^c, E^d. S, indicates a strike plate secured to the frame or body of the vehicle in which is journaled a roller T over which the latch bolt is adapted to pass when the door is closed;—the roller 85

rolling over the inclined portion E^d on the underside of the bolt forces the door upwardly thus overcoming any tendency of the latter to sag. U and U' are vertically disposed rollers journaled in the strike plate 90 at right angles to the roller T, against which the long beveled face E^b of the latch bolt is adapted to bear upon closing the door. The bolt E is forced back by the rollers U and U' against the action of the spring G 95

when the door is closed, and upon the rollers passing the apex between the inclined faces E^b and E^c, of the latch the roller U', in conjunction with the beveled portion E^c of the latch serves to assist in maintaining 100 the door in a tightly closed position and thus overcomes any tendency of the latter to rattle.

Having thus described my invention what I claim is:—

1. A latch for doors comprising a spring actuated bolt having its projecting end beveled on its lower horizontal face and in opposite directions to each other on its inner and outer side faces, a strike plate adapted 110 to be secured to the door casing to receive the end of the bolt, a roller journaled hori-

zontally in the strike plate, adapted to act upon the inclined lower face of the bolt to overcome any tendency of the door to sag and a pair of rollers journaled vertically in 5 the strike plate, adapted upon closing the door to force the bolt back against the action of its spring and when closed to act upon the outer face of the bolt to maintain the door in a tightly closed position and to reduce 10 friction upon the operation of the bolt.

2. A mortise latch for doors; comprising a bolt beveled at the outer end on its lower horizontal and inner and outer vertical faces with a shank extending rearwardly from 15 the enlarged end of the bolt; a bracket secured to the latch casing having an opening to guide and support the shank; a spring adapted to bear against the enlarged end of the bolt and against the bracket to urge the 20 bolt outwardly; lugs projecting from said bolt; a rack bar housed within the latch casing having means at one end to engage the lugs on the bolt; a rocking handle mounted upon a spindle extending trans- 25 versely through the latch casing; a gear secured to the spindle adapted to mesh with the rack bar, whereby the bolt may be withdrawn upon operating the handle; a strike plate to receive the end of the latch; rollers 30 journaled in the strike plate adapted to act upon the inclined faces of the bolt, whereby the bolt may be forced backwardly independently of the rack bar,—to secure the door against sagging,—and to reduce friction upon the operation of the bolt.

3. A mortise latch for doors comprising a

bolt beveled upwardly from its lower horizontal face at the outer end and toward each other from its inner and outer vertical faces; a shank extending rearwardly from the enlarged end of the bolt; a bracket secured to the latch casing having an opening for the passage of the shank; a spring sleeved upon the shank bearing respectively against the enlarged end of the bolt and the bracket, 40 whereby the bolt may be urged outwardly; a pair of spaced lugs integral with the bolt; a rack-bar housed within the latch casing having laterally extending arms at one end overlapping the lugs of the bolt; a spindle 45 journaled in the walls of the latch casing; handles for manually rocking the spindle mounted upon the ends of said spindle; a gear secured to the spindle in mesh with the rack-bar; a strike-plate to receive the 50 beveled end of the latch; a roller journaled horizontally in the wall of the strike-plate, adapted to act upon the lower inclined face of the bolt, to prevent sagging of the door and a pair of vertically disposed rollers 55 journaled in the strike plate in adjacent relation to each other, adapted upon closing the door to force the bolt backwardly against the action of its spring and to reduce friction upon the operation of the bolt. 60

In testimony whereof, I sign this specification in the presence of two witnesses.

JOHN A. WHITTAKER.

Witnesses:

S. E. THOMAS,
JOHN CONSIDINE.
